[57] CLAIM

The ornamental design for a device for catching fecal samples when using a toilet stool, as shown and described.

DESCRIPTION

FIG. 1 is a top perspective view of the device for catching fecal samples when using a toilet stool;

FIG. 2 is a top plan view of the device;

FIG. 3 is a side elevation of FIG. 2, the opposite side being a mirror image thereof;

FIG. 4 is a bottom plan view of the device;

FIG. 5 is an end elevation looking from right to left at FIG. 2;

FIG. 6 is an end elevation opposite that of FIG. 5.

FIG. 1

FIG. 2

FIG. 4

FIG. 3

FIG. 5

FIG. 6
